SHAVING DEVICE

Mathew Andis and Matthew G. Andis, Jr.,
Racine, Wis., assignors to Andis Clipper Company, Racine, Wis., a corporation of Wisconsin

Application February 6, 1937, Serial No. 124,416

8 Claims.

(Cl. 30—43)

This invention relates to improvements in shaving devices.

The invention relates more particularly to shaving devices of the type having a reciprocating cutter driven by an electric motor or other suitable means and movable beneath a slotted face engaging part whereby the device may be used without soap or other beard softening agent to greatly facilitate the shaving operation.

In shaving devices of this type it has been found necessary to have the slotted face engaging surface of extreme thinness where the hair on the face is contacted and guided into the slots, and in most prior devices this face engaging portion has been made so thin as to require support to prevent it from flexing. Heretofore the face engaging portion has been slotted entirely across its width, and the cutter therebeneath has been relied upon to prevent flexing. In addition, the face engaging part has been formed with integral supporting sides to further hold and strengthen the thin slotted member.

It is an object of the present invention to provide a shaving device having a face engaging member so constructed as to provide hair guiding portions of extreme thinness, which portions nevertheless maintain themselves in rigid condition without danger of flexing, whereby there is no necessity for support from the cutter or for the use of integral supporting sides.

A more specific object of the invention is to provide a device as above described wherein the face engaging member is slotted only at the edges, said slots being of limited length, and wherein said edges are reinforced against the possibility of flexing, by a strengthening downwardly extending flange of minute size, said flange also being slotted and serving to provide a smooth skin contacting surface and an effective comb for lifting up and guiding the hair to shearing position.

A further object of the invention is to provide a shaving device having a face engaging member formed with a solid center portion and with slots extending inwardly from opposite edges, the slots along one edge being of less width than the slots along the opposite edge, whereby the edge having the slots of less width may be employed for shaving the neck and other tender portions and whereby the opposite edge may be employed for shaving the face proper to the end that the utmost comfort and most effective results may be obtained.

A further object of the invention is to provide a shaving device in which the comb portion,

face engaging member, and cutter are so constructed and disposed with respect to one another that all cut hair falls exteriorly of the head, thereby eliminating the necessity of cleaning the interior of the head or of removing parts to effect said cleaning.

A still further object of the invention is to provide a device as above described wherein the ends of the head are closed by plates which prevent cut air from entering said ends.

A still further object of the invention is to provide a shaving device comprising a handle portion and head wherein novel means is utilized for removably anchoring the head in position in the handle.

With the above and other objects in view, the invention consists of the improved shaving device and all its parts and combinations as set forth in the claims and all equivalents thereof.

20 In the accompanying drawings illustrating one complete embodiment of the preferred form of the invention in which the same reference numerals designate the same parts in all of the views:

25 Fig. 1 is a plan view of the shaving device (actual size), parts being broken away and shown in section;

30 Fig. 2 is an enlarged sectional view taken on line 2—2 of Fig. 1 showing the method of anchoring the head to the handle;

35 Fig. 3 is an enlarged longitudinal sectional view through the shaving head, a fragment being shown in full;

40 Fig. 4 is a top view of the shaving head, parts being broken away and shown in section;

45 Fig. 5 is a sectional view taken on line 5—5 of Fig. 4;

Fig. 6 is an end view of the shaving head;

Fig. 7 is a perspective view of the cutter member on an enlarged scale;

Fig. 8 is a fragmentary perspective view of the face engaging member on a much exaggerated scale;

Fig. 9 is a perspective view on an enlarged scale illustrating a modification wherein comb members are supported by the end guards;

Fig. 10 is a perspective view of a face engaging member for use in connection with the form of the invention illustrated in Fig. 9;

50 Fig. 11 is an enlarged sectional view through the head showing the construction when the modified parts of Figs. 9 and 10 are used; and

55 Fig. 12 is a fragmentary perspective view showing another form of face engaging mem-

ber which may be used in lieu of the member illustrated in Fig. 10.

Referring more particularly to the drawings, the numeral 16 designates a hollow handle portion which is preferably formed of two complementary half sections 17 and 17'. The handle forms a housing for a suitable driving device such as an electric motor 18, and said motor may have a drive shaft 19 projecting rotatably through a partition 20 and into a recessed outer end portion 21.

The recessed outer end may have one side wall formed with an inwardly extending pin 22, which is preferably of metal and may have its opposite side wall provided with a plurality of inwardly projecting pins 23 which are preferably formed of rubber or other resilient material.

Referring now more particularly to the shaving head proper, the numeral 24 designates a supporting block preferably of metal, which block has posts 25 projecting from the upper surface thereof, there being recesses 26 at the upper surface of the block surrounding said posts. One side of the block is also formed with an aperture 27 for cooperation with the pin 22 (see Fig. 2), and the other side of the block is preferably formed with apertures 28 for cooperation with the pins 23. It is thus apparent that the head may be inserted into the handle first by engaging the pin 22 on the shell section 17 with the aperture 27 of the head, then by engaging the pins 23 on the shell portion 17' with the apertures 28 of the head, and then by securing the two handle portions together by means of screws or the like 29. The rubber pins 23 are found to be effective in cushioning against vibration.

A channel-shaped cutter 30 has the upper edges of its side walls flanged outwardly as at 31 and slotted to form a plurality of minute spaced teeth 32. The inner surfaces of the side walls of the cutter are also beveled at their upper portions as at 33. The said cutter has its bottom wall 34 formed with spaced apertures 35, which apertures preferably have straight side portions and rounded ends as shown in Fig. 4. The upper ends of the posts 25 extend through said apertures 35 of the cutter, and said upper ends of the posts are preferably flattened on opposite sides as at 36 to cooperate with the shape of the apertures 35. The drive shaft 19 of the motor may be extended rotatably into a bore 37 of the block 24 and is provided with an eccentrically positioned extension shaft 38 of smaller diameter. The end of the eccentric 38 fits into a slot or recess 39 of a block 40, which block depends from the lower surface of the cutter. As a result of this arrangement, when the shaft 19 is rotated by the electric motor the eccentric 38 causes rapid reciprocation of the cutter member 30.

The face engaging member 41 is preferably of the cross sectional shape shown in Fig. 8 having preferably a depressed or channeled central portion 42, the sides of which extend laterally outwardly as at 43 and 44. The said portions 43 and 44 project outwardly approximately one-sixteenth of an inch and are slotted as indicated. The slots 43' of the edge portion 43 are preferably of less width than the slots 44' of the opposite edge portion 44. It is preferred that the slots 43' be .007 of an inch wide and that the slots 44' be .010 of an inch wide. The material at 43 and 44 is of extreme thinness whereby the cutter moving therebelow will be able to shear the hair close to the skin. Due, however, to the fact that these thin edge portions 43 and 44 are preferably

only one-thirty-second of an inch long on the lower side, there is no trouble with flexing of said portions. Furthermore, in order to strengthen these relatively thin portions, the outer edges thereof are flanged downwardly as at 45 and 46 respectively, said flange being preferably approximately one-sixteenth of an inch long. These flanged portions 45 and 46 are slotted as indicated in Fig. 8 by slots which communicate with the slots 43' and 44' and which form part thereof. The flanged portions 45 and 46 therefore form combs for straightening out and guiding the hair to cutting position. These slot extensions, however, terminate short of the lower end of the flanges 45 and 46 so that there is a minute webbing 47 connecting the spaced teeth at the bottom of the flanges 45 and 46. This minute downward flange and the webbing serve to strengthen the extremely thin slotted portion so that said portion will maintain itself in rigid condition without danger of flexing. There is therefore no need to employ integral sides extending down to the block 24. Nor is there any need to rely upon the cutter for support against flexing.

The face engaging member 41 may have its center channel portion 42 provided with countersunk bolt holes 48 for the reception of bolts 49. The bolts 49 in turn are threaded into the upper ends of the posts 25 to rigidly secure the face engaging member 41 in position over the cutter.

The cutter, it is to be noted from Fig. 7, has its slotted cutting portions 31 movable close against the lower sides of the portions 43 and 44 of the face engaging member and in the channels 50 formed beneath said portions. The beveled surfaces 33 of the cutter member cooperate with complementary bevel surfaces 51 beneath the face engaging member, and said beveled surfaces 51 fit adjacent one another with slight clearance. It is apparent that during shaving the cutting will take place directly beneath the face engaging portions 43 and 44 and that the cut hair will fall out at 51' exteriorly of the head; thus none of said cut hair will get inside of the head to necessitate frequent cleanings.

Surrounding the posts 25 and having their ends seated in the recesses 26 are coil springs 52, which springs tend to yieldingly urge the cutting member into close contact with the side of the face engaging portions 43 and 44. Washers 53 of leather, fiber or other suitable material which are of greater diameter than the narrow portions of the apertures 35 of the cutter are positioned between the outer ends of the coil springs 52 and the cutter member to prevent wear upon the cutter member and to minimize noise and vibration during the operation of the device.

In order to close and substantially seal the ends of the head to prevent cut hair from entering the interior of the head, it is preferred to utilize end plates 54 (see Fig. 6) which fit recesses in the ends of the block 24 and which are secured thereto by screws or the like 55. These plates have lateral extensions as at 56 at their upper ends which prevent the corners of the face engaging member from scratching the face.

From the above it is apparent that applicants have a construction wherein the face engaging member has hair guiding portions of extreme thinness, which portions are nevertheless of such short length and so reinforced by the flanges 45 and 46 that there is no danger of flexing and no need for additional support. It is also apparent that the face engaging member and cut-

ter are so shaped and cooperate with one another in such a way that cut hair falls exteriorly of the head to eliminate the necessity of cleaning. It is also apparent that by using slots of different width on opposite sides of the face engaging member, that increased comfort and efficiency in shaving may be obtained. It is well known that the skin on the neck is relatively loose and more flexible than the skin on the face, and for this reason it is desirable that the slots be narrower when the device is used on the neck. Otherwise there is danger of the skin entering said slots and being nipped or irritated by the cutter. For the major portion of the face, however, it is desirable that the slots be somewhat wider, and the skin being tougher on these latter portions will not be pressed into these wider slots. Applicants' construction therefore provides in one shaving device a construction capable of taking care of both of these conditions. It is contemplated that this concept of having the slots of different width at opposite edges be employed either in connection with a face engaging member having a separate set of slots on each edge or in connection with a face engaging member having continuous slots extending from edge to edge.

It is further to be pointed out that applicants' construction includes yielding means, such as is shown and described in co-pending application Serial No. 92,714, now Patent No. 2,210,110, Aug. 6, 1940, for constantly urging the cutter into close contact with the lower side of the slotted face engaging portions.

Referring more particularly to Figs. 9 to 12 inclusive, a form of the invention is illustrated wherein the downwardly extending flanges 45 and 46 of the principal form of the invention are not carried by the face engaging member, but wherein the equivalent of said flanges, which provide comb or guard members 57 for straightening out and guiding the hair to the cutters and for preventing the teeth 62 or 63 of the face engaging member from injuring the face, are supported by the upper corners of the end plates 54' as shown in Fig. 5. These comb or guard members may be slotted as at 58 with the slots terminating short of the lower edges of the comb members. The ends of the comb members 57 are preferably formed integral with the end plates 54' as shown, but they may be secured thereto in any other desired manner. As a result of this construction, when the end members 54' are secured to the ends of the head by the screws 55, in the manner shown in Fig. 6, the comb members are simultaneously positioned and supported.

In view of the fact that the comb members 57 are carried by the end plates, a face engaging member without depending flanges is employed. One form of said face engaging member 59 is illustrated in Fig. 10, said member preferably having its upper surface tapered toward each edge as at 60 and 61 and having each edge slotted as at 62 and 63. The parts shown in Figs. 9 and 10 may be assembled in the manner shown in Fig. 11 to provide slight spaces 64 between the comb members 57 and the edges of the face engaging member 59. The shaving head is otherwise constructed in an identical manner to the construction heretofore described in connection with the principal form of the invention. It is to be noted that in both forms of the invention the comb members (45 and 46 of Fig. 8,

or 57 of Fig. 9) are so supported that the lower edges are free. Thus the comb members present no obstruction to prevent the cut hair from falling freely into the spaces 51' (Fig. 5) exteriorly of the head. Therefore no cleaning of the shaving head is ever necessary.

As an alternative for the type of face engaging member shown in Fig. 10, the face engaging member 65 of Fig. 12 may be employed, said member being identical to the member heretofore described in connection with Fig. 8, except that the integral depending flanges 45 and 46 of Fig. 8 are omitted. Certain features in common with this invention are also shown, described and claimed in the companion application of applicants herein, Serial No. 124,417, now Patent No. 2,152,677, April 4, 1939.

Although only two forms of the invention have been shown and described, it is obvious that various changes and modifications may be made without departing from the spirit of the invention, and all of such changes are contemplated as may come within the scope of the claims.

What we claim is:

1. In a shaving device, a handle portion formed of complementary half shell sections open at one end, pins projecting inwardly from each of said sections at said open end, and a shaving head having recesses therein cooperable with said pins to hold the head in position in the handle, and means for removably securing the two handle sections together after the head is in place.

2. In a shaving device, a handle portion formed of complementary half shell sections open at one end, pins projecting inwardly from each of said sections at said open end, and a shaving head having recesses therein cooperable with said pins to hold the head in position in the handle, and means for removably securing the two handle sections together after the head is in place, at least one of said pins being formed of resilient material.

3. In an automatic hair shearing unit, a handle member having a relatively flat support, a relatively flat shearing assembly, means removably affixing said assembly to said support, said support having guard ledge elements apart from said affixing means and rising from said support along the end edges of the flat shearing assembly for protecting the latter.

4. Hair shearing apparatus including a handle member, a relatively flat shearing head mounted thereagainst, means attaching the shearing head to the casing, and guard ledge elements apart from said attaching means rising from said handle member and flanking the entire thickness of the end edges of the shearing assembly.

5. In an automatic hair shearing unit, a handle member, a relatively flat shearing assembly, means removably affixing said assembly to the handle member, said unit including guard ledge elements apart from said affixing means, said guard ledges being parts of an integral structure and being fixedly spaced from each other to rise from said handle member and extend along and guard the entire thickness of the end edges of the shearing head.

6. A hair shearing apparatus comprising a handle member having a relatively flat end with a pair of relatively fixed guard ledges rising from the narrower sides thereof, a relatively flat shearing assembly comprising relatively movable plates superposed over said end, means between said ledges removably affixing said shearing assembly with respect to said handle member, the end

edges of said shearing assembly being guarded by said ledges.

7. In an automatic hair shearing unit, a handle member having a supporting end, a shearing assembly superimposed on said supporting end and including a fixed outer member and a reciprocally movable inner member, said fixed outer member having a relatively flat slotted area, means extending through the top of the fixed outer member for removably affixing the shearing assembly in position, and guard ledge elements apart from said affixing means rising from said support along the end edges of the shearing assembly throughout the length of said end edges and positioned to protect the latter and said end 15

edges at the corners of the inner and outer members.

8. A hair shearing apparatus comprising a handle member having a relatively flat end with 5 a pair of relatively fixed guard ledges rising from the narrower sides thereof, a shearing assembly comprising relatively movable plates superimposed over said end, means between said ledges removably affixing said shearing assembly with respect to said handle member, the end edges of said shearing assembly being guarded by said ledges.

MATTHEW ANDIS
